UNITED STATES PATENT OFFICE.

GEORGE W. HADLEY, OF CHICOPEE FALLS, MASSACHUSETTS, ASSIGNOR
OF ONE-HALF OF HIS RIGHT TO T. C. PAGE, OF SAME PLACE.

BREECH-LOADING FIRE-ARM.

SPECIFICATION forming part of Letters Patent No. 232,816, dated October 5, 1880.
Application filed July 12, 1880. (No model.)

To all whom it may concern:

Be it known that I, GEORGE W. HADLEY, of Chicopee Falls, in the county of Hampden and State of Massachusetts, have invented 5 certain Improvements in Breech-Loading Fire-Arms, of which the following is a specification.

My invention relates to breech-loading guns; and the invention consists of an attachment by 10 which the arm can be converted at will from a center-fire to a rim-fire gun, all as hereinafter more fully set forth.

Figure 1 is a side elevation of a gun having 15 my improvement applied thereto, a portion being shown in section. Figs. 2 and 3 are perspective views of the added parts, shown detached to more clearly illustrate their construction.

This improvement is designed more especially for use with the arm known as the "Maynard gun," but is applicable to any gun of a 20 similar construction.

In Fig. 1, B represents the barrel, and A the stationary breech-piece, of the Maynard gun, the construction of which, being well known, need not be specifically described. In 25 this gun, as usually constructed, there is space left between the rear end of the barrel and the face of the breech-piece of about an eighth of an inch, (more or less,) and which space is occupied by the protruding head of the shell ordinarily used in this arm.

As represented in Fig. 1, the firing-pin *a* of this gun is arranged to strike at the center of the cartridge-head, by which it is adapted to the use of center-fire cartridges only, and it is 5 to enable the arm thus constructed to use rim-fire cartridges also that my invention is designed. In order to do this I provide a cap or cup shaped piece, C, (shown detached in Fig. 2,) of the proper size to fit over the face of the 10 breech-piece A, which latter is undercut at its lower side to permit the cap C to fit thereon, as shown in Fig. 1; or, if preferred, the lower side of the cap C may be cut away, in which case it will not be necessary to undercut the 15 breech, as represented. The face or closed bottom of this cap C is made of a thickness sufficient to fill the space between the face of the breech A and the end of the barrel B, as shown in Fig. 1, and on the inner side of this

bottom there is formed a circular recess, *b*, as 50 shown in Figs. 1 and 2, with a small hole, *n*, near its lower side, which extends through the bottom of the cap. I then provide a disk, *d*, (shown detached in Fig. 3,) of the proper diameter to fit loosely in the recess *b*, but somewhat thinner than the depth of the recess, so 55 that when placed therein it will be capable of being moved back and forth for a very short distance. This disk *d* has projecting from its face a small firing pin or point, *c*, so located 60 that when the disk is inserted in the recess *b* this point *c* will rest in the hole *n*, as represented in Fig. 1, the hole *n*, and consequently the point *c*, being located in the proper position to bring the latter directly opposite the 65 flange of the shell D in the chamber of the barrel, which shell is supposed to represent a rim-fire cartridge, or one of that class which has its fulminate located within the hollow flange of the shell.

In the drawings the firing-point is represented as being located to strike the flange at the lower side of the cartridge in the chamber; but it is obvious that it may be located at any point in the circle of the flange, and that, if 70 desired, two or more firing-points may be provided, so as to strike the flange of the shell at different or opposite points simultaneously, though in practice this is not found necessary with the well-primed cartridges of the present 75 day.

The cap C is secured in place by a couple of screws inserted through the holes *l* in its sides, (shown in Fig. 2,) so that to apply or remove the attachment it is only necessary to insert 80 or remove these two screws.

From the foregoing description it will readily be seen that whenever it is desired to adapt the gun to the use of rim-fire cartridges it is only necessary to apply the cap C, with its striker 85 *d*, as shown in Fig. 1, in which case the blow of the hammer is transmitted, through the firing-pin *a*, to the disk or striker *d*, the point *c* of which is thereby driven against the rim or flange of the shell D with sufficient force to ignite the fulminate therein.

When it is desired to use the center-fire cartridges it is only necessary to remove the cap

C, with its striker *d*, when the firing-pin *a* will strike the primer at the center of the shell and fire it in the usual manner.

It will thus be seen that by these means the gun can at any time be changed to use either rim or center fire cartridges, at the same time retaining the original hammer and firing-pin without any change.

Another advantage of this plan is that it can be applied to the guns already in use at a very small cost, and that it in no way interferes with the use of the gun and its ammunition as they already exist.

In Fig. 1 the end of the barrel is represented as being recessed to receive the flange of the shell; but this may or may not be done, as desired. If not done, it will, of course, be necessary to make the bottom of the cap C correspondingly thinner, to allow for the projection

of the cartridge-head. I prefer, however, to make it with the recess, as it enables me to make the bottom or face of the cap and the striker *d* thicker and stronger.

Having thus described my invention, what I claim is—

The combination, in a breech-loading gun, of the firing-pin *a*, arranged to strike at the center of the breech, with the detachable cap C, having the striker *d* located therein in such a position as to be struck by the firing-pin *a*, and having its point *c* arranged to strike at the edge of the chamber, substantially as and for the purpose set forth.

GEORGE W. HADLEY.
